[57] CLAIM

The ornamental design for a combination rebar support
and nailing block, as shown and described.

DESCRIPTION

FIG. 1 is a front elevational view of a combination rebar support
and nailing block showing my new design;
FIG. 2 is a front elevational view thereof, the rear being
identical;

FIG. 3 is a side elevational view thereof, both sides
being identical;

FIG. 4 is a top plan view thereof; and

FIG. 5 is a bottom plan view thereof.

Fig. 1.

Fig. 2.

Fig. 3.

Fig. 4.

Fig. 5.

UNITED STATES PATENT AND TRADEMARK OFFICE
CERTIFICATE OF CORRECTION

PATENT NO. : DES. 272,125
DATED : January 10, 1984
INVENTOR(S) : DAVID A. VAN DOREN

It is certified that error appears in the above-identified patent and that said Letters Patent is hereby corrected as shown below:

In the Description Figs. 1 and 3 should be changed to read as follows:

Fig. 1 is a perspective view of a combination rebar support and nailing block showing my new design;

Fig. 3 is a side elevational view thereof, both sides being identical;

Signed and Sealed this

Tenth Day of July 1984

[SEAL]
